UNITED STATES PATENT OFFICE.

LOUIS G. ABRAMS, OF NEW YORK, N. Y.

WINDOW SCREEN.

Application filed August 24, 1925. Serial No. 52,153.

This invention relates to screens and particularly to the frames thereof, as applied to window and like openings through which it is desirable to allow air to pass but prevent the intrusion of insects, etc.

One of the objects of the invention is to provide a sectional screen having automatic means for length extension to suit requirements, and which is generally applicable to 10 windows of any ordinary type.

A further feature is in the provision of telescopic stay rods and guides combined with stops limiting the ultimate contraction and expansion of the sections, and guide the 15 sections at all times in parallel relation.

Another aim is to produce a screen of unusually strong construction, in which the spring actuating means is concealed and protected from injury, and which presents 20 a neat and attractive appearance.

These and other important objects are achieved in the present invention by the novel and practical construction and combination of elements hereinafter revealed and 25 illustrated in the associated drawing, constituting a component part of this disclosure, and in which:—

Fig. 1 is a partial front elevational view 30 of a conventional type of window, showing the application of an embodiment of the invention.

Fig. 2 is an upper edge or top plan view of 35 the screen, drawn to an enlarged scale and partially broken away to show the construction.

Fig. 3 is a fragmentary transverse sectional view taken on line 3—3 of Fig. 2, and drawn to an enlarged scale.

Fig. 4 is a front elevational view of a 40 modified form of screen.

Fig. 5 is an upper edge view of the same, parts being broken away to show the interior of the frame.

Fig. 6 is a partial plan view of a further 45 simplified form of the invention preferred for general use.

Fig. 7 is a top plan view thereof.

Fig. 8 is a longitudinal sectional view taken on line 8—8 of Fig. 7.

50 Fig. 9 is a transverse sectional view taken on line 9—9 of Fig. 8.

In the drawings the numeral 10 designates the casements of a window containing vertical grooves in which the sash 11 is slid-

ably engaged, the same being shown raised 55 from sill 12.

The screen frame as shown in Figs. 1 to 3 inclusive is composed of two normally upright rectangular bars 14 and 15, fitted to engage in the grooves of the casements on opposite sides of the window, their width being such as to extend inwardly towards each other, as shown in Fig. 1.

Each of the bars contain in their inner faces longitudinal grooves 16 and 17 offset 65 from each other, one being close to the rear surface and the other near the front.

Rigidly fixed in these grooves are the reduced ends of cross rails 18 and 19, arranged in pairs at the top and bottom of the frame, 70 these cross rails carrying, near their inner ends, vertical metal strips 20 and 21 formed into channel shaped cross sections connecting the upper and lower rails and receptive of the edges of screen sheets 22 and 23. 75

The horizontal edges of these screen sheets are held in grooves 24 and 25 in the adjacent sides of the rails 18 and 19, and the opposite ends of the screen sheets are secured in the grooves 16 and 17 of the bars 14 and 15, thus constituting two independent screen sections. 80

Formed in the adjacent faces of both pairs of rails 18 and 19 are registering undercut recesses 26 and 27, extending throughout 85 their length and at the ends of the rails are tenoned blocks 28 and 29 fixed therein to slide freely in the opposite recesses, thus guiding and confining the two screen sections together but permitting relative longitudinal movement. 90

Fixed on the bars 14 and 15, on opposite sides and near their ends, are pairs of rods 30 and 31, slightly offset to extend in spaced parallel relation with the rails 18 and 19 coincident in length therewith, these rods being telescopically received in tubes 32 and 33 similarly engaged on the opposite sides of the bars 14 and 15, and held to the rails 18 and 19 by eyes 34 secured therein. 100

The tubes 32 and 33 are further held in place by pairs of clips 35 coiled therearound and extending from loops 36 enveloping the outer side and edge surfaces of each pair of rails 18 and 19 at the tops and bottoms of 105 the combined frames.

Fixed in the tenon blocks 28 are eyes 37 engaging one of the ends of helically coiled

tension springs 38, disposed in the recesses 26 and 27, these springs being secured at their opposite ends by pins 39 and having the function of drawing the screen sections 5 apart, acting to press the bars 14 and 15, into firm engagement within the window frame recesses.

A finger grip 40 is fixed on one of the vertical bars, as 15, by which the screen sections may be conveniently caused to slide when inserting or removing the same.

Loosely engaged on one of the lower telescopic tubes is a clip 41 carrying a perforated plate 42 which may be fastened to the sill of the window, thus anchoring the screen in position and acting as a reinforcement for the same.

It is to be noted that the rods and tubes offer an opportunity to conveniently display 20 curtains or like draperies if desired in addition to their reinforcing functions.

In the modification shown in Figs. 4 and 5, a simple type of slidable sectional screen is disclosed, the same embodying the characteristic features previously described.

In this construction a pair of bars 50 and 51 contain longitudinal grooves in their inner faces, disposed respectively near their rear and front surfaces, and fixed in the ends 30 of these grooves are the ends of rails 52 and 53.

The rails are engaged, near their opposite free ends, by metal channel connecting strips 54 and 55 adapted to receive the inner end edges of screen sheets 56 and 57, the other edges of which are fixed in grooves in the rails 52 and 53, and bars 50 and 51.

Both pairs of rails 52 and 53 are provided with undercut registering longitudinal recesses 58 and 59 in which are slidably received blocks 60, secured at the ends of the opposed rails, these blocks acting as guides and to confine the pair of frame sections against other than lineal movement.

As a further securing means, screws 61 are passed through elongated slots 62 and 63 in the rails 52 and 53, the screws engaging the blocks 60, and, as shown, constitute holding means for coiled tension springs 64, disposed 50 in the recesses 58 and 59, and act to pull the frame sections outwardly in the manner before described.

In the preferred embodiment of the invention, shown in Figs. 6 to 9 inclusive, a pair 55 of upright bars 70 and 71 fixed at their ends in metal channels 72 and 73 in which they are secured by fastening means 74.

Fixed in the channels, on opposite sides, are strips 75 and 76 containing grooves to 60 receive the upper and lower edges of screen sheets 77 and 78, their outer edges being set in slots in the bars 70 and 71 and their

inner edges fixed in channels 79 and 80 extending from the adjacent ends of the strips 75 and 76.

Formed in the horizontal elements 72 and 73 of the frames, are central longitudinal slots 81 and 82 and passing through these slots are bolts 83, their bodies passing through close fitting openings in the mating frame members and being engaged by nuts 70 at their inner ends.

It will be understood that the channels 73 are sufficiently larger in cross section than the chambers 72 so to receive the same telescopically.

The bolts 83 are engaged with the ends of coiled tension springs 75 which act to draw the two frame sections apart in the manner before described.

In addition, the channels 72 and 73 are sheared at their ends and bent to present in-turned members 86 serving as stops for the elements 70 and 71, and with which registers the strips 75 and 76, the spaces therebeyond forming chambers for the spring 85 and their connections.

From the foregoing it will be seen that simple devices for the purpose stated have been disclosed in their preferred embodiments, but it will be manifest that minor changes may be made, not involving the exercise of invention and without conflicting with the scope of the appended claims.

Having thus described my invention and set forth the manner of its construction and application, what I claim as new and desire to secure by Letters Patent, is:

1. A window screen comprising two like frame sections slidably connected, interengaging means operatively combined with said sections, telescopic elements connecting said sections at their upper and lower free ends respectively, said elements serving as drapery supports, tension springs in the horizontal elements of said sections, and means on said telescopic elements to anchor the screen as a unit.

2. A window screen comprising two similar frame sections arranged to slide one past the other, interengaging means operatively combined with said sections, telescopic elements connecting said sections at their upper and lower free ends respectively, clips encircling said telescopic elements, loops on said clips enveloping the horizontal elements of both screen sections, and tension springs fixed at their ends to the respective frame elements whereby they are normally urged outwardly.

Signed at New York, in the county of New York and State of New York, this 20th day of July, 1925.

LOUIS G. ABRAMS.
